CLAIM

The ornamental design for a three dimensional adjunct, as shown and described.

DESCRIPTION

FIG. 1 is a perspective view of one embodiment of a new design of a three dimensional adjunct shown on a surgical stapling device;

FIG. 2 is an enlarged view of a section of the three dimensional adjunct of FIG. 1;

FIG. 3 is a top view of the three dimensional adjunct of FIG. 1;

FIG. 4 is a bottom view of the three dimensional adjunct of FIG. 1 with the surgical stapling device removed;

FIG. 5 is a left view of the three dimensional adjunct of FIG. 1, the right view being a mirror image thereof;

FIG. 6 is a front view of the three dimensional adjunct of FIG. 1 with the surgical stapling device removed; and,

FIG. 7 is a back view of the three dimensional adjunct of FIG. 1.

The broken lines in the drawings form no part of the claimed design.

1 Claim, 6 Drawing Sheets## Related U.S. Application Data

division of application No. 29/637,769, filed on Feb. 21, 2018, now Pat. No. Des. 882,782.
